(57) **CLAIM**

The ornamental design for a hand held drinking tumbler, as shown and described.

DESCRIPTION

FIG. 1 is a perspective view of a hand held drinking tumbler showing my new design;

FIG. 2 is a front view thereof, the rear view being identical to the front view;

FIG. 3 is a right side elevational view thereof, the left side elevational view being identical to the right side elevational view;

FIG. 4 is a top plan view thereof; and,

FIG. 5 is a bottom plan view thereof.

The broken lines illustrate portions of the Hand Held Drinking Tumbler that form no part of the claimed design.
